(57) **CLAIM**

The ornamental design for a remote control, as shown and described.

DESCRIPTION

FIG. 1 is a perspective view of the remote control.

FIG. 2 is a top view of the remote control.

FIG. 3 is a bottom view of the remote control.

FIG. 4 is a rear end view of the remote control.

FIG. 5 is a front end view of the remote control.

FIG. 6 is a side view of the remote control; and,

FIG. 7 is an opposite side view of the remote control.

The broken lines shown are for illustrative purposes only and form no part of the claimed design.
